DOOR OPERATING MECHANISM

Fred L. Nichols, Minneapolis, Minn.

Application July 16, 1931, Serial No. 551,106

3 Claims. (Cl. 268—64)

- My present invention relates to door operating mechanism and particularly to that type of door operating mechanism wherein fluid is employed as a power transmitting medium between 5 a primary source of power and a door or doors to be operated thereby and generally stated, the invention consists of novel devices and combinations of devices hereinafter described and defined in the claims.
- 10 Among the important objects of the invention is the provision of an extremely simple, comparatively inexpensive and highly efficient device of the class described.
- In the accompanying drawings, which illustrate the invention, like characters indicate like parts throughout the several views.
- Referring to the drawings:
- Fig. 1 is a fragmentary interior view of a building wall having a door-equipped opening 20 therein and illustrating my operating mechanism in operative relation to the doors;
- Fig. 2 is an enlarged detail view of certain parts shown in Fig. 1, with some parts broken away;
- 25 Fig. 3 is a view partly in section and partly in elevation and taken on the line 3—3 of Fig. 2;
- Fig. 4 is a sectional view taken on the line 4—4 of Fig. 2;
- Fig. 5 is an axial sectional view taken on the line 30 5—5 of Fig. 2;
- Fig. 6 is a detail sectional view taken on the line 6—6 of Fig. 2;
- Fig. 7 is a detail sectional view taken on the irregular line 7—7 of Fig. 6;
- 35 Fig. 8 is a diagrammatic view illustrating the electrical and hydraulic hook-up of the mechanism;
- Fig. 9 is an enlarged detail view taken on the line 9—9 of Fig. 1, some parts being shown in section and some parts being shown in full; and
- 40 Fig. 10 is a detail view taken on the line 10—10 of Fig. 9, some parts being shown in full and some parts being shown in section.
- 45 The wall is indicated by the numeral 10, the door opening therein by 11, a pair of doors for the opening by 12 and the door hinges by 13. The pintles of the hinges are indicated by 14.
- 50 The doors 12 are operated from a common primary motive device in the form of a reversible electric motor 15 through hydraulic power transmission mechanism including a suitable rotary fluid pressure pump 16, and a pair of secondary motive devices in the form of fluid pressure motors A that are arranged to be operated from
- the primary motor 15 by fluid delivered thereto under pressure from pump 16. The secondary motive devices, or fluid pressure motors A, are operative one on each of the doors 12 and are mounted one near each side and above the door opening 11.
- 55 The fluid pressure motors A each include a shell-like casing 17 that forms a segmental chamber 18. Each casing 17 is made up of a flat wall 19, a segmental wall 20 formed with a bottom 21, and a removable cover 22. The front and back walls 19 and 20, respectively, are tightly secured together to afford leak-proof joints therebetween by means of stud bolts 23 and the covers 22 are removably but tightly secured in place by stud bolts 24 and afford leak-proof closures for the chambers 18. The motors A are secured in place by bolts or the like 23a.
- Extending axially through the segmental chamber 18 of each casing 17 is a spindle 25 that is journaled at one end in a bearing hole 26 in the bottom 21 of its respective casing and at its opposite end in a bearing boss 27 in the cover 22 of its respective casing. The spindles 25 project upwardly through the bearing bosses 27 and are equipped at their projected ends with rigidly but detachably secured door operating arms 28 that are connected at their free ends to adjacent doors 12 in a manner to be hereinafter described. The bearing bosses 27 are provided with pack nut-equipped stuffing boxes 29, which prevent leakage of fluid therethrough.
- Carried by the spindle 25 of each motor A for pivotal oscillatory movements therewith about the axis of the chamber 18 thereof is an oscillatory piston in the form of a vane 30. These vanes 30 are formed at their edge portions, beyond their respective cooperative spindles 25, with grooves 31 in which grooves are seated outwardly spring-pressed sealing strips 32 that seat against adjacent portions of their respective casings and reduce leakage of fluid, by the vanes, to a minimum. To further prevent leakage of fluid between portions of the chambers, divided by the vanes and their cooperating spindles, the walls 19 of the casings A are formed opposite the spindles 25 with grooves 33 that extend parallel to the axis of the spindles and which grooves are fitted with sealing strips 33, which are spring-pressed against the spindles.
- Extending through the bottom of each casing 17 and communicating with the chamber 18 thereof, one on each side of the vane 30 in the chamber, are fluid passages or ports 35 and 36. It will be apparent that when fluid is forced

under pressure into a chamber 18 through a co-operating port 35, the vane 30 in that chamber and its co-operating spindle 25 and arm 28 will be moved thereby in a counter-clockwise or door closing direction and when fluid is forced into a chamber 18 through its co-operating port 36, the vane and its spindle and arm will be moved thereby in a clockwise direction or door opening direction.

10 By reference particularly to Figs. 6 and 7, it will be noted that the bottom 21 of the casings 17 are each formed with a cylindrical valve chamber 37 that is connected by means of fluid passages 35^a and 36^a respectively, to the ports 35 and 36, respectively. Communication between these passages 35^a and 36^a through their connected valve chambers 36 and consequent short circuit of fluid between ports 35 and 36 is normally prevented by means of needle valves 38 that work in spaced parallel holes 39 in a plug-like member 40. The holes 39 are each aligned with a passage 35^a or 36^a. Interposed between the inner end of the plug 40 and the bottom of the valve chamber 37 is a suitable gasket 41 that is provided with holes 41 that afford communication between the holes 39 in the plug 40 and aligned passages 35^a or 36^a. The plug 40 is forced in the chamber 37 and is pressed tightly against the gasket 41, which gasket prevents leakage of fluid between the passages 35^a and 36^a or past the plug 40. The bottoms or inner ends of the holes 39 in the plug 40 are reduced to afford seats 42 for the tapered inner ends of the needle valves 38 and said holes are connected back of the seats 42 at 43 so that when the needle valves 38 are moved off of their respective seats 41 communication will be afforded between the passages 35^a and 36^a thereby rendering their respective motor inoperative and free to be turned manually.

40 The needle valves 38, in a particular valve casing 37, are carried in common by and project from the head 44 of a plunger 45 that works through a cap 46 closing that valve casing. These plungers 45 at their outer ends are pivoted to the ends of opposed toggle arms 47, the other ends of which toggle arms are pivoted to the intermediate portions of levers 48. The levers 48 at their inner ends are pivotally attached to the bottoms of their respective motors near opposite sides of the valve casings thereof and at their outer ends said arms are connected by an adjustable tension spring 49. These springs 49, through the arms 48, toggle arms 47 and plunger 45, hold the needle valves 38 seated, as shown by full lines in Figs. 6 and 7, under ordinary fluid pressures existing during operation of the fluid pressure motors but said spring will be overcome by excessive pressure produced in the system, in which latter case the springs 49 will yield and permit its co-operating needle valves to be moved off of their seats by excessive pressure applied against the inner end of one of said valves. The purpose of these excessive pressure operated valves 38 is the provision of means for automatically rendering their respective motors inoperative in case some obstacle is placed in the path of a co-operating door. By reference to dotted lines in Fig. 6 it will be seen that the valves 38 are moved outwardly by excessive fluid pressure until their heads 44 engage caps 46 that act as stops for the valves and that when the valves are thus positioned the toggle arms 48 are positioned on or slightly beyond their dead centers so that the action of the pressure applied by the springs 49 to the toggle arms through the levers 48 will hold the parts locked

in their inoperative positions, shown by dotted lines until the parts are manually moved inward to their extreme dead center positions.

In order to open both doors 12 simultaneously, it is necessary that the motors A be operated, from the motor 15, simultaneously in reverse directions and to this end the port 35 of the right-hand motor A and port 36 of the left-hand motor A are connected together and to like sides of the pump 16 by pipes 50 and a T connection 51 and port 35 of the left-hand motor A and port 36 of the right-hand motor A are connected together and to the opposite side of pump 16 by pipes 52 and a T connection 53.

As a means for manually rendering either of the door operating motors A inoperative independent of the other thereof, I interpose, between the pipes 50 and 52 leading to each motor A, a normally closed manually controlled valve 53^a. These valves 53^a, when closed, do not effect operation of their respective motors A but when opened permit free circulation of fluid through and between the pipes 50 and 52, independent of said motors and therefor render the motors inoperative. The valves 53^a are provided with operating arms 53^b and operating strings 53^c.

The reversible electric motor 15 is of the well-known commercial form which is provided with three leads, to wit: a common lead 54 and reversing leads 55 and 56. This type of motor 30 operates in one direction when it is energized through reversing lead 55 and common lead 54 and operates in an opposite direction when it is energized through reversing lead 56 and common lead 54. Driving connection between the motor 35 15 and pump 16 is afforded by means of a suitable coupling 15^a.

The motor 15 may be supplied with current from any suitable source such as a customary domestic light supply line comprising leads 57 and 58. In the particular arrangement illustrated, the common lead 54 of the motor is connected directly to supply circuit lead 58. The reversing lead 56 is independently connectable to the supply circuit lead 57 through either or each of two branch leads 59 that have normally closed trip switches 60 interposed one in each thereof, a lead 61, a manually operated single pole double throw control switch 62 and a lead 63. The reversing lead 55 is connectable to the supply circuit lead 57 through either one or each of two branch leads 64 that have normally closed trip switches 65 interposed one in each thereof, a lead 66, the manually controlled single pole double throw switch 62 and the lead 63.

The manually operated control switch may be located in any desired position but will preferably be situated outside of the building where it can conveniently be operated by drivers of cars who wish to open the doors before entering or to close the same after departing therefrom.

The trip switches 60 and 65 are located one of each on each fluid pressure motor A and are arranged to be automatically controlled by the door operating arms 28, the intermediate portions of which extend parallel to the axis of their respective motors A and move about and in spaced relation to the segmental portions of said motors. These trip switches 60 and 65 each comprise a casing 67 having a bottom 67^a of insulating material on which is mounted a fixed contact 68, and an intermediately pivoted contact arm 69 that is normally closed with fixed contact 68 by means of a spring 70. The trip switch casings 67 are mounted on the covers 22 of the casing of motors

A and are normally securely held in place at their outer ends by certain of the stud bolts 24 and washers 24^a and at their inner end by split collars 71 that are telescoped over and have quite 5 tight frictional engagement with the bearing bosses 27.

The trip switches are independently adjustable about the axis of their respective motors A when the bolts 24 holding the same are loosened.

10 The bolts 24 holding the outer ends of the trip switches are, it will be noted, longer than other bolts 24 of the covers 22 of said motors and are interchangeable therewith to permit securing of the trip switches in any desired position on the covers 22. The outer ends of the pivoted switch arms 69 project radially beyond the segmental portions of the motors A into the path of travel of cams 72 that are carried by the arms 28. By particular reference to Fig. 3 it will be noted that the said outer ends of the switch arms 69 are curved in opposite directions to provide cam engaging surfaces 69^a.

15 In the arrangement illustrated and, as will hereinafter be more clearly pointed out, the cams 25 72 on the switch arms 28 engage the pivoted arms of their cooperating trip switches 65 and open said switches when the arms 28 are near their extreme door closed positions and engage the pivoted arms 69 of their cooperating trip switch 20 60 and open said switches when the arms 28 are near their extreme door open positions.

25 Preferably and as illustrated, the connection between each of the door operating arms 28 and its respective door is made through an independent automatically operated door latching mechanism 73. Each of these door latching mechanisms 30 73 include a plate 74 carried by its respective door near the top thereof, a latch bolt 75 working through a bearing lug 76 formed as 35 part of the plate 74, a pair of toggle arms 77 and a coil compression spring 78. The latch bolts 75, when in an extended operative position, as 40 illustrated, project above the tops of their respective doors and enter holes 79 in members 80 45 that are secured to the wall 10 above the door opening 11. At their lower end portions, these latch bolts 75 are formed with enlarged heads 81 50 that afford seats for the lower ends of the springs 78, which springs work on said bolts and are compressed between the bearings 76 and heads 55 81 of the bolts and tend to withdraw their bolts to an inoperative position. The outer end of one of the toggle arms 77 is pivotally attached to the head 81 of bolt 75 at 82 and the outer end of the 60 other toggle arm 77 is pivotally attached to a lug 83 formed on the plate 74. The inner ends of the 65 toggle arms 77 are pivotally connected together and to one end of a link 84 at 85. The other ends of the links are provided with slots 86 that work 70 loosely over bolts 87 that are carried by the free ends of the arms 28. The bolts 87 fit loosely in the slots 86 so as to permit slight vertical sliding and rocking movements of said links thereon. It should here be noted, by reference to full lines 75 in Fig. 9, that the inner ends of the toggle arms are moved slightly beyond their dead centers and engage the plate 74 when the bolts are extended and act to lock said bolts against accidental retraction by their respective springs 82.

70 Initial movements of the arms 28, in a door opening direction, retract the latch bolts 75 out of the holes 79 and into engagement with stops 88 on the plate 74 and continued movements of said arms cause opening of the doors. The 75 springs 82 are sufficiently strong to prevent pro-

jecting of the bolts 75 during closing movements of the doors but will be overcome by pressure applied by the motors A after the doors come to a stop in a completely closed position and act as a base of reaction.

5 By means of these latch mechanisms 73, the doors 12 are automatically positively locked closed independent of the locking action of the operating mechanism so that doors can not be opened, by force applied directly to the doors, 10 even to such slight extent as would often be permitted by slack motion in the operating connection or faulty operating mechanism.

Operation

15

To open the doors 12, the movable arm of the manually controlled switch 62, indicated by 62^a, is closed with lead 61 thereby connecting the motor reversing lead 56 to supply lead 57 through lead 63, said lead 61, branch leads 59 and their 20 now closed trip switches 60 and causing the operating mechanism to operate in a direction to open the doors. Initial door opening movements of the operating arms 28 will release the latches 25 63 and continued movement thereof will be imparted to the doors. When the doors come approximately to their desired maximum open positions the cams 72 on the arms 28 will engage the arms 69^a of the trip switches 60 and open said 30 switches thereby automatically breaking the circuit and rendering the operating mechanism inoperative. The trip switches 65 are obviously permitted to close under initial opening movements but such will be ineffective at this time because the circuit therethrough is opened by 35 switch 62.

To close the doors the arm 62^a of switch 62 is closed with lead 66 thereby connecting reversing lead 55 to supply lead 57 through lead 63, said lead 66, branch leads 64 and their now closed trip switches 65. The mechanism will now operate to close the doors and the spring 78 of the latches 63 will resist door closing pressure and prevent projection of the latch bolts 75 until the doors are completely closed and act as a base of reaction, 45 at which time they will be overcome by pressure of said arms and permit projection of the bolts 75. The trip switches 65 will be opened by the cams 72 when the arms 28 have completed their door closing and latching operations and will 50 again render the mechanism inoperative.

40 What I claim is:

1. In a door operating mechanism a fluid pressure motor having a pressure chamber, a piston mounted in said chamber and having operating 55 connections extending therefrom to a door, fluid connections leading to said chamber at opposite sides of the piston, means for alternately forcing fluid into the chamber through opposite of said connections to operate the piston in reverse directions, a fluid by-pass between the fluid connections at a point ahead of the motor, valve means interposed in the fluid by-pass and subject to opening pressure by fluid in the system, and means operating on the valve means to maintain 60 the same closed against the opening action of the fluid under normal pressures but permitting opening of the valve means under excessive pressures and operative on said valve means subsequent to such opening under excessive pressure 65 to hold the same open subject to manual manipulation.

2. In a door operating mechanism a fluid pressure motor having a pressure chamber, a piston mounted in said chamber and having operating 70 75 connections extending therefrom to a door, fluid connections leading to said chamber at opposite sides of the piston, means for alternately forcing fluid into the chamber through opposite of said connections to operate the piston in reverse directions, a fluid by-pass between the fluid connections at a point ahead of the motor, valve means interposed in the fluid by-pass and subject to opening pressure by fluid in the system, and means operating on the valve means to maintain the same closed against the opening action of the fluid under normal pressures but permitting opening of the valve means under excessive pressures and operative on said valve means subsequent to such opening under excessive pressure to hold the same open subject to manual manipulation.

- connections extending therefrom to a door, fluid connections leading to said chamber at opposite sides of the piston, means for alternately forcing fluid into the chamber through opposite of said connections to operate the piston in reverse directions, a fluid by-pass between the fluid connections at a point ahead of the motor, valve means interposed in the fluid by-pass and subject to opening pressure by fluid in the system, and yielding means operating on the valve means to maintain the same closed against the opening action of the fluid under normal pressures but permitting opening of the valve means under excessive pressures and operative on said valve means subsequent to such opening under excessive pressure to hold the same open subject to manual manipulation.
3. In a door operating mechanism a fluid pressure motor having a pressure chamber, a piston mounted in said chamber and having operating connections extending therefrom to a door, fluid connections leading to said chamber at opposite sides of the piston, means for alternately forcing fluid into the chamber through opposite of said connections to operate the piston in reverse directions, a fluid by-pass between the fluid connections at a point ahead of the motor, inwardly closing valve means for controlling the fluid by-pass, an opposed pair of levers pivotally mounted beyond opposite sides of the valve means, toggle arms pivotally carried by the valve means at their inner end portions and being pivotally connected at their outer end portions to free portions of opposite of said levers, said toggle arms diverging inwardly toward the valve means when the valve means is in an inwardly closed position and being movable by the valve means, under the action of excessive fluid pressure, at least to aligned dead center positions, and yielding means tending to move the levers toward one another and the valve means to a closed position.

FRED L. NICHOLS.
